A. H. Heisey & Company, Newark, Ohio

Application April 12, 1950, Serial No. 9,151

Term of patent 14 years

(Cl. D36—2)

To all whom it may concern:

Be it known that I, T. Clarence Heisey, a citizen of the United States of America and a resident of Newark, in the county of Licking and State of Ohio, have invented a new, original, and ornamental Design for a Glass Bowl or Similar Article, of which the following is the specification, reference being had to the accompanying drawing, forming a part hereof.

Figure 1 is a side elevational view of a glass bowl or similar article, showing my new design.

I claim:

The ornamental design for a glass bowl or similar article, substantially as shown.

T. CLARENCE HEISEY.
